SYRUPER.

1,072,412.

Specification of Letters Patent.

Patented Sept. 9, 1913.

Application filed April 24, 1911. Serial No. 622,898.

To all whom it may concern:

Be it known that we, WILLIAM C. ANDERSON and ALBERT R. THOMPSON, citizens of the United States, residing at San Jose, in 5 the county of Santa Clara and State of California, have invented certain new and useful Improvements in Syrupers, of which the following is a specification.

Our invention relates to the class of can-syruping machines, or, as they are commonly known in the art, "syrupers".

Our invention is especially intended for the syruping of open topped cans, and it embodies and includes provisions for holding 15 the fruit down in the cans while the syrup is being supplied, and for insuring, by a proper disposition of any excess of syrup, the exact amount of syrup remaining in the cans, without regard to the volume supplied.

These are the objects of our invention and they are attained, briefly stated, by swinging perforated presser-caps adapted to timely cover the cans and hold the fruit in 25 while the syrup is passing through said caps into the cans; and by means for tilting the cans as they enter and pass through the machine, so that the excess of syrup will overflow the can rims and thus provide for 30 a given level in said cans when they again assume an upright position.

In these means, together with novel details of construction, adjustment, arrangement and combination, our invention consists as will be more fully explained and understood by reference to the accompanying drawings in which—

Figure 1 is a plan view of our syruper. Fig. 2 is a vertical sectional view of the 40 same.

1 are the supporting legs to which is bolted a drip pan 2, which is to receive the excess of syrup spilled from the cans. 3 is a non-rotatable centrally disposed 45 post to which the non-rotatable parts are fixed, and upon which the rotatable parts are mounted and turn.

4 is a sprocket the hub 5 of which is journaled on the post 3. This sprocket is 50 formed or provided with an annular upris- ing flange 6.

7, in Fig. 1, is the inleading track and 8 the outleading track.

9 is a traveling carrier chain which leads 55 in over track 7, engages and semi-circles the

sprocket 4 and leads out over track 8, thereby rotating said sprocket. This carrier chain 9 has its articulated links disposed vertically or on edge, and certain ones of said links, at suitably spaced intervals, are 60 provided or formed with flights 10, which in their course around the sprocket 4, overlie on one side the outer portion of the sprocket surface and on the other side they rest upon a steady track 11, which rises from the 65 rim of the drip-pan 2, the surface of said track being higher than the surface of the sprocket. The cans 12, rest upon the vertically disposed links of the carrier chain 9 between the flights 10 thereof, and are carried to the rim of the sprocket where their bases overlie both said rim and the track 11.

13 is a can-tilting plate inclining centrally, its upper portion on its inner side being formed or provided with a rail 14. 70 The functional part of the can-tilting plate 13 encircles one-half the machine, but at its ends it has tangential extensions 13' to furnish safe guides for the entering cans.

It will now be seen that as a given can 80 reaches the beginning of the tilting rail 14, said can will be tilted over inwardly until the inner side of its base rests upon the surface of the sprocket, as shown in Fig. 2, and it will be held at this angle until it reaches 85 the other side of the machine, where passing from the rail 14, it will return to an upright position, being so placed, as is shown, as to be overweighted outwardly.

The cans 12 being of the open-topped type, without caps, require some means to hold the fruit down while the can is tilted and the syrup is being supplied. For this purpose we provide the holding pressure-caps 15. These caps are adapted to fit 90 down upon and cover the tops of the cans. They are perforated as shown at 16, in Fig. 1, to admit the syrup, while confining the fruit; and on their inner sides the under surface of the caps is grooved as shown at 15' in Fig. 2, to allow the syrup to spill out. The caps have a flange 17 to properly direct 95 the entering syrup. These presser caps 15 are carried by arms 18, pivoted at 19 to an annular bracket 20, the hub 21 of which is 100 fitted upon the hub 5 of the sprocket 4 and rotates therewith. Behind their pivotal points at 19, the arms 18 are extended and have their extremities 22 engaging the 105 groove of a cam 23 fixed on the non-rotata- 110

ble post 3. This cam 23 has its groove on two levels, as shown in Fig. 2, the higher level acting to force the presser cap 15 down upon the can, and the lower one serving to lift the cap from the can. Rotatably mounted upon the upper end of the post 3 is a hollow distributing head 24 from which radiate pipes 25 fitted with down-turned filling ends 26. In each filling end is a controlling valve 27.

28 is a pipe leading from the source of syrup supply. This pipe leads into the hollow head 24 through a suitable stuffing box.

29 are bracket arms which at their outer ends are fitted on the filling ends 26 of the pipes 25, and at their inner ends are bolted to the annular bracket 20, this connection being for the purpose of rotating the pipe system in unison with the other rotating

20 parts.

The valves 27 are of any suitable type. They are automatically opened and closed by the following mechanism. Each valve 27 has an operating handle 30, which at its 25 inner extremity is provided with a down-turned stud 31. Fixed upon the central post 3 is a plate 32, which has a groove 33, said groove being concentric with but inside of the circular path of travel of the handle 30 studs 31 when said handles are in position to keep the valves closed. On the plate 32 is a gate 34 which is pivoted at 35 and is adapted to swing outward to intersect the path of travel of said stud 31 when the 35 valve is closed, as is shown in Fig. 1. The free end of the gate 34 is connected by a link 36 with a crank 37 on a turnable spindle 38 passing up through the hollow of the central post 3, said crank emerging through 40 and playing in a slot in said post. A spring 39 connected with the gate, as shown in Fig. 1, holds it normally in out of the path of travel of the stud 31.

40, (indicated in dotted lines in Fig. 1) 45 is a turnable shaft, the upper end of which carries an arm 41, which normally lies in the path of that can 12 which is about to enter the machine. The lower end of the shaft 40 has a crank 41' which is connected 50 by a link 42 with a crank 43 on the lower end of the spindle 38. When the can 12, which is just entering the machine, comes in contact with the arm 41, it will cause the shaft 40 to turn, and this movement through 55 the cranks 41 and 43 and rod 42 will turn the spindle 38. The turning of this spindle, through its upper crank 37 and link 36 will swing the gate 34 outward across the path of the stud 31. When this stud, therefore, 60 comes in contact with the gate 34, said stud and its valve handle will be forced inward and will thence-forward travel in this position, thereby opening and keeping open the valve. At the far end of the plate 32 is the 65 closing cam 32' so shaped as to direct the

stud 31 and the valve handle out again thereby closing the valve and cutting off the supply of syrup. If there should be no can entering the machine, the gate 34 will remain in its normal position and the stud 31 will not be forced in, and the valve of that pipe will not, therefore, be opened. The closing cam 32' is fitted by means of bolts 33' in the groove 33, so that said cam may be set in any position on the plate in order to close the valve at any desired time previously determined upon. Now, in order to make provision for varying the angle at which the can is tilted while being supplied with syrup, so that the machine may be suited to the ideas of different users with respect to the amount of syrup it should contain, we call attention to the following adjustments.

In the flange 6 of the sprocket 4 are seated stop screws 44 which bear on the cans. By setting these in, the cans will be permitted to tilt to the least angle; by setting the screws out, the cans will tilt to a greater angle. Thus any angle may be chosen, and the amount of syrup retained in the cans may be regulated to suit the user. As provision is thus made to vary the tilting angle of the cans, it is obvious that provision must also be made for the adjustment of the presser-caps and their operating cam, in order to conform to the altered angle of the cans. This we accomplish by making the fitting between the hub 21 of the annular bracket 20 which carries the presser caps, 100 and the hub 5 of the sprocket 4 a slip joint, so that the bracket may be raised or lowered and may be fixed in position by a set screw 45. In like manner the presser-cap cam 23 is made vertically adjustable on the central post 3, and is fixed by a set screw 46. Finally as the annular bracket 20 is adjustable vertically, and as the connected pipe system will move with it, we make the valve operating plate 32 also vertically adjustable 105 and fix it with a set screw 47.

The operation of the machine is as follows:—The open-topped cans 12 filled with fruit are carried in continuous succession into the machine by the carrier chain 9. This 115 chain is also the driving mechanism of the machine and through the sprocket 4 all the moving parts are rotated about the central post 3. As the first can reaches the tilting rail 14 it is tilted inward to the angle previously determined upon by the adjustment of the stop screws 44. At the same time, the overlying presser-cap 15 descends upon the top of the can and holds the fruit in. Also at the same time, the can, by contact with the arm 41 effects, through the connections described, the outward swing of the gate 34, so that the stud 31 of the valve handle 30 will be forced inwardly, thereby opening the valve 27 of the overlying syrup supply pipe. 130

The syrup now flows down through the perforated presser-cap 15 into the can. This continues until the can is near the other side of the machine, when the excess of syrup 5 spills over the rim of the tilted can through the grooves 15' of the presser cap, and thus leaves the can with only the amount of syrup provided for by its tilted position. The spilled syrup falls into the drip-pan 10 and may be disposed of in any manner. At this time also the valve closes, and the can being free of the tilting rail, will resume its upright position and be carried out of the machine. Succeeding cans are subjected 15 to like operations, and the work is continuous.

Having thus described our invention what we claim as new and desire to secure by Letters Patent is—

20 1. In a syruper, the combination of a traveling support for the cans; means for tilting the cans as they travel; means for confining the fruit in the tilted cans while traveling; and syrup-supplying means traveling 25 with the cans for delivering syrup to them as they travel in tilted position.

2. In a syruper, the combination of a traveling support for the cans; means for tilting the cans as they travel; perforated 30 presser-caps adapted to cover the tops of the cans while traveling in tilted position; and syrup supplying means adapted to deliver the syrup through the presser-caps to the cans as said cans travel in tilted 35 position.

3. In a syruper, the combination of a traveling support for the cans; means for tilting the cans as they travel; means for confining the fruit in the tilted cans while 40 traveling; syrup-supplying means for said cans as they travel in tilted position; controlling means to control said syrup supplying means; and means called into operation by the traveling cans for automatically operating said controlling means.

4. In a syruper, the combination of a rotatable can carrier provided with seats for carrying the cans; means for tilting the cans to cause the surplus material to be 50 discharged; and syrup supplying pipes rotating with said carrier and so disposed relatively to the cans as to deliver the syrup to them while they are traveling in a tilted position.

5. In a syruper, the combination of a rotatable can carrier provided with seats for carrying the cans; means for tilting the cans as they travel; means for confining the fruit in the cans while traveling in tilted 60 position; and syrup supplying pipes rotating with said carrier for delivering syrup through the fruit confining means to the cans while they are traveling in a tilted position.

6. In a syruper, the combination of a ro-

tatable can carrier provided with seats for carrying the cans; means for tilting the cans as they travel; perforated presser-caps rotating with the carrier and adapted to cover the tops of the cans while traveling in tilted position; and syrup supplying pipes rotating with said carrier for delivering syrup through the presser-caps to the tilted cans. 70

7. In a syruper, the combination of a rotatable carrier provided with seats for carrying the cans; a rail for tilting them to cause the surplus material to be discharged; and syrup supplying pipes rotating with said carrier for delivering syrup to said 80 tilted cans. 75

8. In a syruper, the combination of a rotatable carrier provided with seats for carrying the cans; a tilting rail for tilting them to rest upon the carrier while tilted; means for varying and defining the angle at which the cans are tilted; and syrup supplying pipes rotating with said carrier for delivering syrup to said tilted cans. 85

9. In a syruper, the combination of a rotatable carrier provided with seats for carrying the cans; a tilting rail for tilting them to rest upon the carrier while tilted; adjustable stops on the carrier adapted to vary and define the angle at which the cans 95 are tilted; and syrup supplying pipes rotating with said carrier for delivering syrup to said tilted cans. 90

10. In a syruper, the combination of a rotatable carrier provided with seats for carrying the cans; a tilting rail for tilting them to rest upon the carrier while tilted; perforated presser-caps rotating with the carrier adapted to cover the tops of the cans while traveling in tilted position; and syrup 100 supplying pipes rotating with said carrier for delivering syrup through the presser-caps to said tilted cans. 105

11. In a syruper, the combination of a rotatable carrier provided with seats for carrying the cans; a tilting rail for tilting them to rest upon the carrier while tilted; perforated presser-caps rotating with the carrier adapted to cover the tops of the cans while traveling in tilted position; pivoted 110 arms carrying said presser-caps; a cam for swinging said arms to move the presser-caps to and from the cans; and syrup supplying pipes rotating with said carrier for delivering syrup through the presser-caps 115 to said tilted cans. 120

12. In a syruper, the combination of a rotatable carrier provided with seats for carrying the cans; a tilting rail for tilting the cans to rest on the carrier while tilted; means for varying and defining the angle at which the cans are tilted; perforated presser-caps rotating with the carrier adapted to cover the tops of the cans while traveling in tilted position; means for ad- 125 130

justing said presser-caps to suit the tilting angle to which the cans are adjusted; and syrup supplying pipes rotating with said carrier for delivering syrup through the presser-caps to said tilted cans.

13. In a syruper, the combination of a non-rotating central post; a can support rotatable about said post; means for tilting the cans as they travel; perforated presser-caps rotating with the can support; a cam fixed on the central post; connections with the presser-caps and operated by the cam to effect the movement of said caps to the cans, to cover them while traveling in a tilted position; and syrup-supplying pipes rotating with said can support for delivering syrup through the presser-caps to the tilted cans.

14. In a syruper, the combination of a non-rotating central post; a can carrier rotatable about said post; and provided with seats for the cans; means for tilting the traveling cans; perforated presser-caps adapted to cover the traveling tilted cans; a bracket secured to and rotating with the can support; arms pivoted to said bracket and carrying the presser-caps; a cam fixed on the central post engaging and operating the arms of the presser-caps; and syrup supplying pipes connected and rotating with said bracket for delivering syrup through the presser-caps to the tilted cans.

15. In a syruper, the combination of a non-rotating central post; a can support rotatable about said post; and provided with seats for the cans; means for tilting the traveling cans on said seats; perforated presser-caps adapted to cover the traveling tilted cans; a bracket secured to and rotating with the can support; arms pivoted to said bracket and carrying the presser-caps; a cam fixed on the central post engaging and operating the arms of the presser-caps; syrup supplying pipes connected and rotating with said bracket for delivering syrup through the presser-caps to said tilted cans; controlling means for controlling said pipes; means fixed on the central post to operate the controlling means; and connections operated by the traveling cans for throwing said means into and out of action.

16. In a syruper, the combination of a non-rotating central post; a sprocket wheel rotatable about said post; a driving chain semi-encircling the sprocket and provided with seats for the cans; means for tilting the traveling cans on said seats; perforated presser-caps adapted to cover and uncover the traveling tilted cans; a bracket secured to and rotating with the sprocket; arms pivoted to said bracket and carrying the presser-caps; a cam fixed on the central post engaging and operating the arms of the presser-caps; syrup supplying pipes connected and rotating with said bracket for delivering

syrup through the presser-caps to said tilted cans; valves for controlling said pipes; arms to open and close the valves, said arms having studs; a plate fixed on the central post and having a deflecting gate for throwing the studs inwardly to open the valves; a contact arm in the path of the cans; power transmitting connections between said contact arm and deflecting gate; and a cam on the plate acting on said studs to throw them out again and close the valves.

17. In a syruper, the combination of a non-rotatable central post; a sprocket rotatable about said post; a driving chain semi-encircling the sprocket and provided with seats for carrying the cans; a tilting rail for tilting the traveling cans over on their seats to rest on the sprocket; adjustable stops on the sprocket for varying and defining the angle at which the cans are tilted; perforated presser-caps adapted to cover and uncover the traveling tilted cans; arms carrying said caps; a bracket fitted to and adjustably connected with the sprocket; pivotal connections between the adjustable bracket and the presser-cap arms; a cam fixed on the central post and engaging the presser-cap arms to swing them; syrup pipes connected and rotating with the presser-cap bracket; valves for controlling said pipes; operating arms for the valves; a plate adjustably carried upon the central post, and having means to operate the valve arms to open and close the valves; and means controlled by the traveling cans for throwing said valve operating means into and out of action.

18. In a syruper, the combination of a non-rotating central post; a sprocket wheel rotatable about said post; a driving chain semi-encircling the sprocket and provided with seats for the cans; means for tilting the traveling cans on said seats; perforated presser-caps adapted to cover and uncover the traveling tilted cans; a bracket secured to and rotating with the sprocket; arms pivoted to said bracket and carrying the presser-caps; a cam fixed on the central post engaging and operating the arms of the presser-caps; syrup supplying pipes connected and rotating with said bracket for delivering syrup through the presser-caps to said tilted cans; valves for controlling said pipes; arms to open and close the valves, said arms having studs; a plate fixed on the central post and having a deflecting gate for throwing the studs inwardly to open the valves; a contact arm in the path of the cans; power transmitting connections between said contact arm and deflecting gate; and a cam on the plate acting on said studs to throw them out again and close the valves, said cam being adjustable upon the plate to vary the times at which the valves close.

19. In a filling machine, the combination of a rotatable receptacle carrier provided

with seats for carrying the receptacles, means for tilting the receptacles to cause the surplus material to be discharged, and material supplying pipes rotating with the carrier for delivering material to said tilted receptacles.

20. In a filling machine, the combination of a rotatable receptacle carrier provided with seats for carrying the receptacles, means for tilting the receptacles to rest upon the carrier while tilted, means for varying and defining the angle at which the receptacles are tilted, and material supplying pipes rotating with said carrier for delivering material to said tilted receptacles.

21. In a filling machine, the combination of a rotatable receptacle carrier provided

with seats for carrying the receptacles, means for tilting the receptacles to rest upon the carrier while tilted, adjustable means on the carrier adapted to vary and define the angle 20 at which the receptacles are tilted, and material supplying pipes rotating with said carrier for delivering material to said tilted receptacles.

In testimony whereof we have signed our 25 names to this specification in the presence of two subscribing witnesses.
